UNITED STATES PATENT OFFICE.

LESTER P. CLARK, OF FANWOOD, NEW JERSEY, ASSIGNOR OF ONE-HALF TO ANTHONY L. STEBOR, JR., OF PLAINFIELD, NEW JERSEY.

BLOW-OUT PATCH.

1,310,156.

Specification of Letters Patent. Patented July 15, 1919.

Application filed April 13, 1918. Serial No. 228,447.

To all whom it may concern:

Be it known that I, LESTER P. CLARK, a citizen of the United States, residing in Fanwood, in the county of Union and State 5 of New Jersey, have invented new and useful Improvements in Blow-Out Patches, of which the following is a specification.

My invention relates to blow-out patches or devices for locally strengthening a pneumatic tire when perforated or weakened. 10 My invention has particular reference to inside blow-out patches which are interposed between the shoe and inner tube of a combination pneumatic tire to prevent the inner tube from bursting through a perforation or weak spot in the shoe under pressure of the contained air.

Blow-out patches are usually constructed of the same materials as tire shoes, and for 20 similar reasons, since the former are subjected to substantially the same strain and wear and tear as the latter. But although rubber, or rubber and linen have sufficiently good road wearing qualities and tensile 25 strength, it has been found that a serious difficulty arises from the extreme flexibility or flimsiness of such materials. The inner tube tends constantly to force the patch through the blow-out or weak spot, thus 30 causing a bulge in the patch which becomes more and more pronounced until it fails to protect the perforation, and in some cases is even carried bodily through the shoe by the bursting of the inner tube. The displacement 35 of the patch is assisted by the rotation of the vehicle wheel, which causes the patch to be alternately flattened out, (as when adjacent to the ground), and bulged at other points of the revolution. Relative motion is 40 thus set up between the shoe, patch, and inner tube, and this motion will ordinarily be constant in direction, so that eventually the blow-out or weak spot will be uncovered. In order to remedy the above mentioned 45 defects, various expedients have been proposed, such as fastening devices which secure the blow-out patch in place; but such devices are expensive and complicated, moreover, they usually require careful manipulation 50 in order to adjust them in place, causing great inconvenience when repairs are made on the road.

The object of my invention is to produce a blow-out patch which will not creep or 55 bulge, and at the same time to avoid the use

of special fastening devices, so that the patch may be permanently adjusted in working position by simply inserting it between the inner tube and the shoe.

In its broadest aspect my invention consists in a blow-out patch which is stiffer or more rigid than those now in use. I have discovered that by the use of auxiliary stiffening means a blow-out patch can be produced which will have little or no tendency 60 to creep or become displaced, presumably because the stiffened patch will not bulge, thus eliminating, partially at least, the relative motion between the patch and shoe which ultimately causes a displacement sufficient 65 to defeat the purpose for which the patch is used.

Other features of my invention relate to details of construction in the illustrative embodiment of my invention shown in the accompanying drawings and hereinafter described. 75

In the drawings:

Figure 1 is a view, partly broken away, of the outer or tread surface of a preferred 80 embodiment of my invention.

Fig. 2 is a longitudinal, central, sectional view of the same, and

Fig. 3 is a transverse sectional view of an assembled pneumatic tire with my patch 85 in operative relation to a blow-out or perforation in a shoe or casing.

Referring more particularly to the drawings, the blow-out patch there shown consists of a body portion 1, and auxiliary 90 stiffening means 2. The patch as a whole should be curved both transversely and longitudinally so as to approximately conform, as regards curvature, to an inflated pneumatic tire. In Fig. 3 I have shown a shoe 95 or outer casing 4, having a blow-out perforation 5, and an inner inflated tube 6. The outer or tread surface of the patch is preferably modified by the addition of means for increasing the frictional co-efficient of 100 the surface with respect to the inner surface of the shoe or casing with which it contacts; such means comprising in the illustration, suction cups 3. These suction cups or their equivalent will counteract any 105 tendency which there may be toward displacement of the patch. But it should be understood that I do not consider this feature absolutely essential and my invention is not limited in this respect.

The body, 1, may consist of any suitable material, as rubber or linen, or a built-up fabric of rubber and linen, or other suitable material. The stiffening member 2 in 5 the illustration consists of a loosely woven fabric of strips or wires of a material which is more rigid than the material of which the body portion is made up. While any degree of rigidity will answer the conditions of my invention, I prefer to employ 10 strips or wires of high elasticity and some degree of flexibility in order that the patch may approximately follow the changes in form which are undergone by a pneumatic tire when in use.

As a result of my experiments, I prefer 15 a patch in which a fabric 2, of fairly stiff piano wire is wholly embedded in a molded sheet of rubber 1. The reinforcing fabric 20 2 should be smaller than the body portion 1, in order to leave a soft, yielding margin 4 at the edges of the patch. This soft margin 4 protects the inner tube and shoe from the stiff, preferably metallic, member 2.

If constructed in the manner described, 25 the rubber will be very intimately associ-

ated with the stiffening member 2, particularly if the mesh of 2 is sufficiently large so that the inner and outer layers of rubber will be held together by a large number of 30 connecting cords of rubber, passing through the meshes.

It will be obvious that within the scope of my invention many forms of stiffening members and many modes of uniting them 35 to the patch can be devised; and I do not wish to be understood as limiting myself to any of the details of construction shown.

I claim:

1. A blow-out patch, comprising a re- 40 inforging wire fabric, coated on both sides with rubber to form a body of substantially even thickness throughout its main body portion, and having on its outer surface vacuum cups; whereby the patch may be 45 placed and held without additional holding devices in any position within a casing.

2. A blow-out patch such as set forth in claim 1, in which the vacuum cups have central bosses.

L. P. CLARK.
